UNITED STATES PATENT OFFICE.

BENJAMIN F. MAYO, OF SALEM, MASSACHUSETTS, ASSIGNOR TO UNITED SHOE MACHINERY CORPORATION, OF PATERSON, NEW JERSEY, A CORPORATION OF NEW JERSEY.

MACHINE FOR OPERATING UPON SHOES.

1,399,784.

Specification of Letters Patent. Patented Dec. 13, 1921.

Application filed June 6, 1918. Serial No. 238,519.

To all whom it may concern:

Be it known that I, BENJAMIN F. MAYO, a citizen of the United States, residing at Salem, in the county of Essex and State of Massachusetts, have invented certain Improvements in Machines for Operating upon Shoes, of which the following description, in connection with the accompanying drawings, is a specification, like reference characters on the drawings indicating like parts in the several figures.

This invention relates to machines for operating upon shoes, being here shown in connection with a heel-attaching machine.

An object of the invention is to so organize a work-supporting member, as a jack-post, and a work-positioning member, as a band-clamp, that the work and positioning members may be brought readily into correct engagement without danger of defacing the work by the relative movement between it and said positioning member. As heel-attaching machines are commonly arranged, as the jack post carrying the shoe to which the heel is to be attached is swung in for the nailing operation, the band-clamp, which has been raised by its connection with the jack post to remove it from the path of the loader mechanism, descends so that the clamp and shoe converge to the operating position. When they thus meet through a simultaneous movement, it may not be easy to properly introduce the rear portion of the shoe into the clamp, and the lower edge of the band may drag across and rub the upper. In accomplishing the previously-mentioned object, I provide for control of the movement of the work-positioning member independently of the work-supporting member. The positioning member, which as already indicated, may in a heel-attaching machine be the band-clamp, does not, as heretofore, move only under the influence of the work-supporting member or jack post, but may be temporarily secured against movement for later release to move independently.

A further object of the invention is to reduce the breakage of work gages and to render them readily repairable when broken. In heel-attaching machines, the breast gages, and particularly those which hold the top lifts, may be subjected to stresses which bend or break them. This may arise when the

top lift is thinner than the gage, so that direct pressure is brought upon the latter as the top lift is forced on. Under such conditions, the gage may be pressed downward through the yield permitted at the clearance between the gage and swing plate and between the swing plate and nail block. There is also sometimes a depression formed in the swing plate extending beneath the gage, which is employed to produce a convex bottom to the heel. This throws a further strain upon the gage. I arrange the gage to receive such pressure with less liability to breakage by forming it in sections extending along the edge of the work, one of which sections is carried by and is yieldable upon the other. Preferably, the gage sections are connected by a spring, which is shown as located in recesses in the breast-engaging arm of the gage and is secured thereto by rivets.

An additional object of the invention is to provide for maintaining in correct relation a delivery mechanism and means for actuating an element thereof. In some shoe machinery, of which the herein illustrated heel-attaching machine furnishes an example, a movable mechanism and a means for actuating it are situated upon parts of the machine which may not be in proper alignment, so that the actuating movement is interfered with. Considering the specific instance of the heel-attaching machine, a loader arm may be pivoted upon the frame of a machine, while the element which trips the nail gate of the loader block is carried by the nail block cross-head. The release of the gate to deliver the nails to the nail block is effected by the contact of the gate with its trip when the cross-head is in its normal position, but an adjustment of the stroke of the cross-head, or even an incorrect initial relation of the parts, may cause the trip to lie outside the plane of movement of the gate, so that the tripping of the latter is not accomplished. In correcting such defects, I have so arranged the delivery or loader mechanism and the actuating or tripping means that their relative positions may be varied to correspond to the variation in the normal relation of the elements which support them. This adjustment, particularly in connection with loader mechanisms for heel-attaching

machines, is preferably applied to the tripping means. The time of coöperation of the delivery mechanism and actuating means therefor may also be varied, I having here 5 shown the tripping member adjustable in angular position.

The accompanying drawings illustrate a form of my invention embodied in a heel-attaching machine.

10 Figure 1 thereof is a side elevation of a portion of a heel-attaching machine, illustrating more particularly the relation between the jack post and the band-clamp;

15 Fig. 2 is a top plan view of the heel and top lift holding mechanism and the loader mechanism, the jack post and band-clamp being removed;

Fig. 3 is a broken detail in rear elevation of the upper portion of the jack post;

20 Fig. 4 is a perspective view of the cross-head with the swing plate mounted thereon;

Fig. 5 shows in perspective a portion of the breast gage; and

Fig. 6 is a vertical sectional detail through 25 the center of the swing post stud illustrating the manner of holding the nail gate trip thereon.

In the frame 10 are mounted for movement in the usual or any desired manner the 30 oppositely arranged work-spindle 12 and cross-head 14. The cross-head carries the nail block 18, through openings in which act the drivers 20. At the lower extremity of the spindle 12 is mounted the jack slide or 35 carrier 16, between lugs 22 depending from the under side of which is pivoted upon a pin 23 the jack post, including upper and lower sections 24 and 26, respectively. The section 26 is shown as mounted for movement 40 longitudinally of the section 24, the sections being locked in their normal position by a latch 30 pivoted upon the section 26 and having its tripping portion extending downwardly along the section. At the bottom 45 of the section 26 is the usual pin 32 arranged to enter the opening of a last, as illustrated at L, this carrying the shoe S to which a heel is to be attached. The upper extremity of the post section 24 is divided, and between the separated portions, upon the pivot pin 23 as its fulcrum, is mounted a connecting lever 34. One arm of this lever is provided with a hook 36 connected, by a chain 38 passing over a sprocket 40 journaled upon the slide 16, to a vertically 50 movable slide 42. This slide 42 is mounted in ways in a member 44 upon the frame and carries a band-clamp 46, the band 48 of which is arranged to receive the rear portion 55 of the shoe upper, the lower edge of said band entering the rand crease, to hold it in position for the heel-attaching operation. The other arm of the lever 34 contacts with a screw 50 threaded through the front of the 60 post section 24. As the jack post is swung 65

outwardly upon its pivot this screw forces down the hook 36 of the lever correspondingly, exerting tension upon the chain 38. Formed upon a segmental portion of the lever 34 is a series of ratchet teeth 52, with which coöperates a latch device furnished by a detent 54 sliding in a sleeve or casing 56 threaded into one of the lugs 22. A spring 58 surrounding a spindle 60 of the detent between its body portion and a head of the casing 56 maintains the coöperation of the detent and ratchet teeth. To withdraw the detent from engagement with the teeth, a hand lever 62 is pivoted to the spindle 60 and fulcrumed upon an extension 64 from the lug 22 below the sleeve 56. It extends downwardly along the jack section 24, where it may be manipulated conveniently by the operator. There is also shown the usual detent 66 pivoted upon the section 24 of the jack post and arranged to engage a depression 68 in one of the lugs 22, thus serving to temporarily retain the jack post in its work-receiving position.

For the purpose of describing this feature of the invention, it will be assumed that the heel-attaching operation has just been completed, the jack post, lasted shoe and band-clamp being related as indicated in dotted lines in Fig. 1. At this time 90 the chain 38 is slack. As the work spindle rises in the reversal of the measuring movement, the work and band-clamp remaining in the nailing position, the chain becomes taut. The operator then swings out the 95 jack post to the position illustrated in full lines at the right of Fig. 1, at the same time removing the heeled shoe. In this movement of the jack post the lever 34 acting through the chain raises the band-clamp a distance equal to the measuring movement, the ratchet teeth 52 slipping beneath the detent 54, and when the detent 100 66 engages its depression the band-clamp is locked by the engagement of the detent 105 54 and teeth. Consequently, when the jack post is returned to the operating position, the band-clamp will be held at such a height that the lower edge of the band will be at the level in which the rand crease 110 will move when the jacked shoe is carried by the jack post into the operating position. When, therefore, the operator applies another lasted shoe to the pin 32 and forces down the jack post, the shoe enters the 115 band with a substantially rectilinear movement while said band is stationary, so that the engagement is perfect and there is no relative movement tending to scratch the work. The operator thereupon depresses 120 the levers 62 and 30. This releases the connecting lever 34 and the jack post section 26 so that the band-clamp and work may be dropped together until the heel seat of the shoe rests upon the heel H carried by 125 130

the swing plate. When the treadle is depressed and the jack post descends in its measuring movement, the jack post sections are restored to their normal relation, latched 5 together by the lever 30 ready for the application of the heel to the shoe.

Pivoted upon the cross-head 14 above the nail block 18 is a swing plate 70, this turning about a stud 72 projecting upwardly 10 from the rear of the cross-head. Upon the swing plate are carried holders for heels and top lifts, these including forks 74 and 76, respectively, adjustable in guides 78, and breast gages 80 and 82, respectively. The 15 heel gage may be constructed and arranged in the customary manner, being drawn toward its fork in the guide 78, as is also the top lift gage, by a spring 84. The gage 82 has two arms, one of which, designated by 20 the numeral 86, is guided as is the heel gage, while the contact arm of the gage is formed in two sections 88 and 90. The section 88 extends for a relatively short distance from the arm 86 and is shown as integral therewith. It is continued by the alined section 25 90 to the end guide 92. The section 90 is connected to the section 88 for relative movement toward and from the nail block by a spring 94, here shown as of leaf form 30 and situated in recesses 96 in the gage sections, the depth of these recesses being such that the top of the spring is flush with, or at least not higher than the top of the gage. The spring may be secured to the sections 35 35 by pairs of rivets 98, 98. The contact arm of the gage is shown as extending over a depression 100 in the swing plate, though this depression may or may not be used. When present, it acts to form a convex 40 surface upon the top lift as it is spanked on the heel.

If, as is sometimes the case, the top lift is thinner than the contact arm of the gage, the overhanging portion of the heel will 45 bear upon it, and by moving it the amount of the clearance spaces between it and the swing plate or between the latter and the nail block or into the swing plate depression may tend to break or deform the contact 50 arm. On account, however, of the independence of the sections, the outer one 90, upon which this pressure is brought, may yield sufficiently to usually prevent damage, or, if breakage occurs, it will be in the spring 55 94. This part is inexpensive and may be readily renewed by cutting off the rivets, inserting a fresh spring and riveting it in place.

Nails are delivered to the nail block by a 60 loader mechanism, including an arm 102 pivoted at 104 upon the frame 10 and carrying a perforated block 106, beneath which is pivoted the nail-supporting gate 108. A spring 110 exerts its tension to swing the 65 nail gate from beneath the block, the gate

being retained in its nail-supporting position by a latch projection 112. The gate is actuated to cause its release from the projection by contact with a tripping projection 114. This projection I prefer to 70 mount upon the swing plate stud, and, since this stud is carried by the cross-head, the normal relation of which may be changed by adjustment of its actuating mechanism, I 75 adjustably support the projection on the stud to compensate for this. To this end, the stud 72 has its end projecting through the swing plate threaded at 116, this threaded portion being engaged by a nut 118 having an upward extension 120 externally 80 threaded. Threaded upon the extension 120 is a sleeve 124 vertically adjustable by being turned upon the extension. It is held in the position to which it is moved by a check nut 126 contacting with its upper 85 extremity and also threaded upon the extension. At its lower end is an annular flange 128, upon which rests the hub 130 of the tripping projection 114. The hub is free to turn about the sleeve, and near the 90 upper end of the hub said sleeve is threaded externally at 132 to receive a nut 134, which when turned down against the hub fixes it as to its angular position.

If in the use of the machine it is found 95 that the plane in which the nail gate moves when the loader block is swung over the nail block does not bring it into proper engagement with the trip 114, the location of this tripping projection may be varied 100 vertically by the organization just described. This is accomplished by releasing the nut 126 and turning the sleeve 124 up or down until the projection 114 is found to be correctly engaged by the latch 112. The 105 nut 134 being freed from its contact with the hub 130, the projection may be turned upon the flange 128 until the time at which the gate is tripped is such that the nails are 110 properly delivered to the holes in the nail block.

The machine in its general operation may differ in no essential respect from the usual heel-attaching machines of this type and this will not particularly be described. 115

Having fully described my invention, what I claim as new and desire to secure by Letters Patent of the United States is:

1. In a machine of the class described, a movable work-supporting member, a work-positioning member, connections arranged to communicate movement from the supporting member to the positioning member, and means for controlling the movement of the positioning member independently of 120 the supporting member.

2. In a machine of the class described, a movable work-supporting member, a work-positioning member, connections arranged to communicate movement from the sup- 125

- porting member to the positioning member, and means for temporarily securing the positioning member while leaving the work-supporting member free for movement.
5. 3. In a machine of the class described, a movable work-supporting member, a work-positioning member, connections arranged to communicate movement from the supporting member to the positioning member, means for temporarily securing the positioning member against movement, and means for releasing the positioning member to move independently of the supporting member.
10. 4. In a machine of the class described, an oscillatory work-supporting member, a work-positioning member movable with the supporting member in one direction and independently movable in the opposite direction, and a latch effective to retain the positioning member at the point to which it is moved by the supporting member.
15. 5. In a machine of the class described, an oscillatory work-supporting member, a work-positioning member movable with the supporting member in one direction and independently movable in the opposite direction, a latch effective to retain the positioning member at the point to which it is moved by the supporting member, and a lever situated adjacent to the supporting member for releasing the latch.
20. 6. In a machine of the class described, a carrier, a work-supporting member pivoted thereto, a connecting member pivoted adjacent the supporting member and having contact therewith to move with it in one direction, a movable work-positioning member joined to the connecting member, and means mounted on the carrier and engaging the connecting member for retaining it in the position to which it is moved by the supporting member.
25. 7. In a machine of the class described, a carrier, a work-supporting member pivoted thereto, a connecting member pivoted adjacent the supporting member and having contact therewith to move with it in one direction, a movable work-positioning member joined to the connecting member, means mounted on the carrier for retaining the connecting member in the position to which it is moved by the supporting member, and a release member for the retaining means extending along the supporting member.
30. 8. In a heel-attaching machine, a movable jack post, a movable band-clamp, connections between the jack post and band-clamp, and means for controlling the movement of the band-clamp independently of the jack post.
35. 9. In a heel-attaching machine, a pivoted jack post, a band-clamp, a lever movable with the jack post and connected with the band-clamp, and a latch for the lever.
40. 10. In a heel-attaching machine, a pivoted jack post, a band-clamp, a lever having one arm coöperating with the jack post, a member connecting the other arm of the lever with the band-clamp to raise said band-clamp, and a latch for holding the band-clamp in its raised position.
45. 11. In a heel-attaching machine, a pivoted jack post, a band-clamp, a lever movable with the jack post and connected with the band-clamp, a latch for the lever, and a hand lever coöperating with the latch and extending adjacent to the jack post.
50. 12. In a heel-attaching machine, a slide, a jack post pivoted thereon, a lever fulcrumed upon the slide and coöperating with the jack post, a band-clamp connected to the lever, and a detent mounted upon the slide and engaging the lever.
55. 13. In a heel-attaching machine, a slide, a jack post pivoted thereon, a lever fulcrumed upon the slide and having a series of ratchet teeth, a band-clamp connected to the lever, and a detent mounted upon the slide and engaging the teeth.
60. 14. In a heel-attaching machine, a slide, a jack post pivoted thereon, a lever fulcrumed upon the slide and coöperating with the jack post, a band-clamp connected to the lever, a detent mounted upon the slide and engaging the lever, and a lever coöperating with the detent and extending along the jack post.
65. 15. In a machine of the class described, means for applying pressure to the work, and a gage consisting of sections extending along the edge of the work, one of the sections being carried by the other and arranged to yield thereon in the direction of said pressure.
70. 16. In a machine of the class described, means for applying pressure to the work, a gage consisting of sections situated in alignment along the edge of the work, and a spring extending in alignment with the sections and being connected thereto.
75. 17. In a machine of the class described, means for applying pressure to the work, a work-gage consisting of two sections formed with recesses lying in the path of the work, and a spring situated in the recesses and being secured to the sections.
80. 18. In a machine of the class described, means for applying pressure to the work, and a work-gage consisting of two sections formed with recesses lying in the path of the work, a spring situated in the recesses, and rivets securing the springs to the sections, the spring and securing means being flush with the surfaces of the sections.
85. 19. In a heel-attaching machine, a breast gage including a member having a guiding arm and a breast-engaging arm, the breast-engaging arm being in sections, and a spring connecting the sections and permitting
- 90
- 95
- 100
- 105
- 110
- 115
- 120
- 125
- 130

movement of a section longitudinally of the heel-breast.

20. In a heel-attaching machine, a breast gage including an angular member having a guiding arm and a breast-engaging arm, the breast-engaging arm being divided into sections near the angle between the arms, and a spring extending parallel to the sections and being secured thereto to hold the sections against separation longitudinally of the breast-engaging arm.

21. In a heel-attaching machine, a nail block, and a breast gage mounted over the block and having a section yieldable in the direction of said block and a relatively fixed section.

22. In a heel-attaching machine, a nail block, a breast gage mounted over the block and being divided transversely, and a spring extending over the division and being secured to the gage at each side thereof to support one of the divided portions upon the other.

23. In a machine of the class described, supporting elements variable as to their normal relation, a movable delivery mechanism and an actuating member therefor carried, respectively, by said elements, and means constructed and arranged for varying the position of the delivery mechanism and actuating member to correspond to the variation in the normal relation of the supporting elements.

24. In a machine of the class described, movable delivery mechanism, actuating means with which an element of the delivery mechanism contacts in its movement, the normal relation of the delivery mechanism and the actuating means being variable, and means constructed and arranged for varying the position of the actuating means to correspond to the variation in said normal relation.

25. In a heel-attaching machine, a frame, nail delivery mechanism movable thereon, a movable operating member, actuating means for the nail delivery mechanism mounted on the operating member, and means constructed and arranged for varying the position of the actuating means to correspond to the movement of the operating member.

26. In a heel-attaching machine, a frame, loader mechanism movable on the frame and having a nail gate, an adjustable cross-head, a tripping member for the nail gate carried by the cross-head, and means constructed and arranged for adjusting the tripping

member to compensate for the adjustment of the cross-head.

27. In a machine of the class described, movable delivery mechanism, actuating means with which an element of the delivery mechanism contacts in its movement, the normal relation of the delivery mechanism and the actuating means being variable, and means constructed and arranged for varying the position of the actuating means to correspond to the variation in said normal relation and for also varying the time of coöperation of the actuating means and the elements of the delivery mechanism.

28. In a heel-attaching machine, a frame, loader mechanism movable on the frame and having a nail gate, an adjustable cross-head, a tripping member for the nail gate carried by the cross-head, and means constructed and arranged for adjusting the tripping member to compensate for the adjustment of the cross-head and for also adjusting the angle of the tripping member.

29. In a tripping device for loader mechanism, a projection, a sleeve surrounding the projection, means for fixing the sleeve in place, a tripping member mounted to turn about the sleeve, and means for fixing the tripping member in the position to which it may be turned.

30. In a tripping device for loader mechanism, a threaded projection, an internally threaded sleeve engaging the projection and being provided with a flange, a nut upon the projection for clamping the sleeve, a tripping member supported by the flange to turn about the sleeve, and means for fixing the tripping member in place upon the sleeve.

31. In a tripping device for loader mechanism, a threaded projection, an internally and externally threaded sleeve engaging the projection and being provided with a flange, a nut upon the projection for clamping the sleeve, a tripping member supported by the flange to turn about the sleeve, and a nut upon the sleeve for clamping the tripping member.

32. In a tripping device for loader mechanism, a stud, a swing plate pivoted upon the stud, a nut upon the stud having an upward extension, a carrier member variable in position along the projection, and a tripping member mounted to turn about the carrier member.

In testimony whereof I have signed my name to this specification.

BENJAMIN F. MAYO.
